[57] ABSTRACT

A handle attaching machine is provided for applying

molded plastic handles to gable-topped cartons such as milk cartons or the like. The machine has an input at one end for receiving the cartons and an output at the other end to expel the cartons after handles have been applied thereto. A conveying path communicates between the input and output of the machine along which cartons are transported, and stop means are provided at separate work stations within the machine to stop transport of the cartons twice, once for punching a hole in the carton and another time for attaching a handle thereto. A magazine-loading mechanism is located on top of the machine to receive a plurality of molded plastic handles in the form of a stack of strips of such handles which are fed to a handle-applying station whereat the handles are severed from the strip and applied to the carton. The handle has bendable side portions which terminate at free ends. One of the free ends has an aperture and the other of the free ends has a deformable stem extending therefrom which passes through the aperture in the carton and the aperture of the first free end. Hammer means are provided at the handle-applying station to cooperate with the handle-applying means permanently to flatten or deform the stem for securing the handle to the carton.

HANDLE ATTACHING MACHINE

BACKGROUND OF THE INVENTION

This invention relates generally to a machine for applying handles to cartons, and more particularly to a machine for applying molded plastic handles to cartons having a gabled-top configuration, such as milk cartons, or the like.

Cardboard cartons for containing liquids or powdered materials are well known. Generally, such cartons, when used for milk, or the like, are covered with a hygienically pure wax substance to form a leak-proof carton. In the past such waxed coated cardboard cartons were limited to relatively small sized containers, such as quarts or half gallons while the larger sized containers, gallons or larger, were of glass or plastic. Because of the increase in weight, the larger containers were provided with handles, such as the well known wire or plastic handle connected about the neck of a gallon milk bottle, which would increase the cost of such containers. However, because of the relative high cost of glass or plastic containers, as compared to a waxed cardboard or the like, it has been found advantageous to provide suitable handles for carrying the larger waxed cardboard containers. One such handle heretofore incorporated takes the form of a unitary molded pliable plastic device having a tab which is folded over the upper ridge of the gable-topped carton and stapled thereto. While this type of handle is well suited for most purposes, it does not readily facilitate pivoting of the handle relative to the carton while pouring from the carton.

Automatic machines for applying the pliable plastic handles to cartons are generally well known. These machines generally include a conveying path through the machine and a handle-applying station which senses the presence of a carton within the machine to fasten a handle to the carton. However, machines heretofore known have a hopper type of handle receiving mechanism which received handles in a disoriented fashion and then shakes the handles through suitable guiding devices to orient the handle for proper application to the carton. This type of machine is relatively complex and expensive and may have the tendency to occasionally improperly orient a handle as it is delivered to the handle-applying station, and thus jam the machine.

Furthermore, machines for applying handles to gable-topped milk cartons are used in dairies where the plastic-coated cartons are filled with milk and sealed at the top end thereof. Generally dairies are equipped with a plurality of pneumatically operated machines which require large air-compressors continuously to run to supply sufficient air pressure in large enough volume for operation of such machines. Any further machinery added to the operation within the dairy which also utilizes large quantities of compressed air for pneumatic actuators would result in additional cost in dairy operation because in many instances, larger air-compressors or air-storage tanks would be required.

SUMMARY OF THE INVENTION

Accordingly, it is an object of this invention to provide a handle-attaching machine which includes an automatic magazine feed mechanism to feed molded plastic handles in strip form to a handle-applying station.

Another object of this invention is to provide a handle-attaching machine to fasten pivotal handles to the upstanding rib of a gable-topped carton.

Another object of this invention is to provide a handle-attaching machine which has hammer means for deforming a stem of the handle being attached by cold flow of the material forming the stem.

Still another object of this invention is to provide a handle-attaching machine which is simple and relatively inexpensive to manufacture and efficient and reliable in operation.

A feature of this invention is the provision of a common cam shaft having sequentially operated cam follower means to perform the various functions of the machine, thus reducing the need for compressed air.

Briefly, the handle-attaching machine of this invention has an input at one end of the machine to receive the cartons and an output at the other end to expel cartons after handles have been applied thereto. A conveying path communicates between the input and output of the machine to transport the cartons therethrough. A first stop arm extends into the conveying path and the carton abuts the arm to stop its movement. The first stop arm defines the location of a punching station whereat an aperture is formed in the upwardly extended ridge of the gable-topped carton. A punching mechanism is located at the end of a hollow arm which is pivoted at the other end thereof. The arm is allowed to move upwardly and downwardly relative to the conveying path so that the punching mechanism at its end can be raised and lowered over the upwardly extending ridge of the carton. An actuating rod extends through the hollow arm and is actuated when the arm is lowered over the upwardly extending ridge of the carton to form the aperture therein at the desired location. The upward and downward movement of the arm together with the linear movement of the punching rod are caused by individual cam surfaces and the cam followers which operate from a common rotatable cam shaft. The arcuate displacement of the lobes of the cams determine the sequence of operation of the punching mechanism.

After an aperture is formed in the upwardly extended ridge of the carton a pushing arm pushes the carton transversely of the conveying path to free it from the stop. The cartons then continue to be transported through the machine along a slanted guide rail, having rollers or the like, to gradually direct the carton back to the linear line of the conveying path.

The carton is then stopped a second time, this being in registry with a handle-applying station whereat the carton is raised from the conveyor. The upward motion of the carton has an extent sufficient to insert the upper ridge of the gable-top between pivotal arms which swing toward and away from the ridge. As the arms swing toward the ridge they pick up a handle from a strip of handles and maneuver the side portions of the handles arcuately so that a stem at one end of the handle passes or threads itself through the aperture in the ridge and threads itself through an aperture in the other side portion of the handle. The pivotal arms hold the side portions of the handle firmly against the upwardly extended ridge of the carton and hammer means are actuated to press the stem with sufficient pressure to cause cold flow action of the material forming the stem. The stem is thus deformed permanently and the handle will at all times remain engaged with the carton. The

handle-applying arms and hammer means are connected to the common cam shaft by suitable cam follower and link members, and similarly are sequentially operated with the remaining portions of the machine.

The machine is provided with a magazine feed mechanism located substantially over the conveying path through the machine. The magazine mechanism is arranged to receive a relatively large stack of strips of handles to be fed therefrom to the handle-applying station. Each strip of handles may, for example, include twenty or more handles held together by severable tabs which are formed during the molding operation of the strip of handles. Twenty-five or more of such strips of handles can be stacked one on top of the other in the magazine for feeding therefrom. The magazine includes a reciprocating pusher extending through a saddle to feed the strips of handles toward the handle-applying station one handle increment at a time. A pair of vertically spaced apart pivotal gates are fashioned with extending fingers to engage and support the stack of handles. The strips of handles are dropped in position on the saddle one strip at a time while the remaining stack of handles positioned over the saddle are supported by the upper pivotal gate. The upper pivotal gate member drops the entire stack on the lower pivotal gate member which, in turn, does not open to position the strip of handles onto the saddle until the first gate member has fully closed to support the stack. This allows feeding of a plurality of strips of handles in stacked fashion such that five hundred or more handles can be loaded into the magazine at a single loading.

Other objects, features and advantages of this invention will be more fully realized and understood from the following detailed description when taken in conjunction with the accompanying drawings wherein like reference numerals throughout the various views of the drawings are intended to designate similar elements or components.

BRIEF DESCRIPTION OF THE DRAWINGS

FIG. 1 is a perspective view of the handle-attaching machine of this invention and shows cartons without handles entering the machine and cartons with handles leaving the machine;

FIG. 2 is another perspective view of the machine of FIG. 1 with the cover portion thereof removed to expose internal portions of the machine;

FIG. 3 is a top somewhat diagrammatic view of the machine with certain portions broken away for clarity and shows a conveying path through the machine and illustrating the various work stations within the machine for applying handles;

FIG. 4 is a fragmentary view of the first stop mechanism within the machine to locate to carton passing therethrough at a punching station;

FIG. 5 is an elevated fragmentary rear view of a portion of the main cam shaft in the machine which drives the various operating mechanisms of the machine;

FIG. 6 is a sectional view taken along line 6-6 of FIG. 5;

FIG. 7 is a sectional view through the machine at the punching station thereof showing the details of the punching mechanism;

FIG. 8 illustrates the punching mechanism lowered over the upstanding ridge of a gable-topped carton for forming the aperture therethrough;

FIG. 9 illustrates the upward movement of the punching mechanism to free the carton before further transport thereof through the machine;

FIG. 10 is a fragmentary and somewhat diagrammatic view of a pushing mechanism and further illustrates the first stop member at the punching station, the pushing mechanism being used to shift the punched carton laterally from the conveying path sufficient to be free of the stop so that it will continue to be transported through the machine;

FIG. 11 is a perspective fragmentary view of a saddle for receiving a strip of handles and a reciprocating feed mechanism to advance the strip of handles one handle increment at a time for feeding the handles into the handle attaching mechanism;

FIG. 12 is an enlarged end view of the feeding mechanism of FIG. 11, taken along the line 12-12;

FIG. 13 is a fragmentary view of the cam shaft of the machine showing a linearly movable cam and cam follower for providing linear reciprocal movement of the handle advancing mechanism of FIGS. 11 and 12;

FIG. 14 is a perspective fragmentary view of a pushing mechanism which pushes the handle to a folded down position after it is fastened to the carton and which serves to sever the then fastened handle from the strip of handles;

FIG. 15 is a perspective fragmentary view of still another portion of the handle feeding mechanism and is used to reciprocate upwardly and downwardly to move the handle feeding member upward and downward during operation and further illustrates a counting switch to count the number of handles fed so that a next strip of handles can be positioned on the saddle of FIG. 11 after the last handle is used;

FIG. 16 illustrates an end view of the magazine-feeding mechanism of this invention used for delivering the handles in strip form to the handle-applying station;

FIG. 17 is a front elevational view of the feeding mechanism of this invention which feeds the strips of handles from the stack onto the saddle of FIG. 11;

FIG. 18 is an end view of the magazine-feeding mechanism showing portions of the dropping gates thereof to position the lowermost strip of handles on the saddle while supporting the remaining stack of handles;

FIGS. 19 through 22 illustrate the sequence of operation of the magazine-feeding mechanism of this invention for lowering the handles therein;

FIG. 23 shows the handle-attaching mechanism in its unactuated position with a carton raised from the conveying path to receive a handle;

FIG. 24 shows the handle-attaching mechanism of FIG. 23 in its actuated position to fasten a handle to a carton;

FIG. 25 shows the handle-attaching mechanism in its unactuated position and is viewed from the output side of the machine to show further details thereof;

FIG. 26 shows the handle-attaching mechanism of FIG. 25 in the actuated position;

FIG. 27 is a top view of the handle-attaching mechanism of FIGS. 25 and 26;

FIG. 28 is an enlarged detail view showing the hammer or compression device used to cause cold flow of the material forming the stem of the handle being attached;

FIG. 29 is a perspective view of a gable-topped carton showing an aperture formed through the upstanding ridge thereof;

FIG. 30 shows a handle attached to the upstanding ridge of the carton of FIG. 29;

FIG. 31 illustrates a container of handles which is comprised of a plurality of strips of such handles in a stack and has an extracting tab extending upwardly therefrom to facilitate removing the stack from the carton in a single maneuver;

FIG. 32 illustrates the stack of handles oriented in position to be inserted into the handle-feeding mechanism of this invention and wherein the extractor strip can be removed upwardly therefrom when the handles are so inserted into the machine;

FIG. 33 is a block diagram illustrating the arrangement of FIGS. 33A and 33B; and

FIGS. 33A and 33B comprise the schematic wiring diagram of the control circuit for the machine of this invention.

DETAILED DESCRIPTION OF THE ILLUSTRATED EMBODIMENT

Referring now to FIG. 1 there is seen a handle-attaching machine which is constructed in accordance with this invention and is designated generally by reference numeral 10. The handle-attaching machine 10 includes an upper support frame 11 movably fastened to a stand 12 so that the operating height of the machine can be adjusted. A cover or hood 13 is provided to cover the operating mechanism within the machine. A passage 14 extends through the machine and defines an input 16 and an output 17 through which a plurality of gable-topped cartons 18 are transported. These cartons are transported through the passage by a conveying apparatus 20.

The gable-topped cartons 18 are suitable for holding liquid or powder such as those used for milk or soap or the like. The handle-attaching machine 10 has a punching station and a handle-applying station, to form an aperture through the upstanding ridge 18a of each carton and to apply a pivotal gripping handle 19 to the carton. This is done causing a rivet-like member or stem at the end of the handle to pass through the aperture in the upstanding ridge and then deforming the rivet to cause cold flow of the material permanently to fasten the handle to the carton.

The conveying path through the machine from the inlet 16 to the outlet 17 can be formed by any suitable conveying apparatus 20, which does not form part of the machine, and may be part of a conveying system along which previously filled cartons are transported to a packaging station or the like. The conveying apparatus 20 in any particular situation may have a given height within a range of heights. Therefore the upper frame 11 is adjustably secured to the stand 12 and this adjustment is effected by an adjusting wheel 22 which threadedly passes through a support beam 23 to shift upstanding guide rail 24 upwardly and downwardly in channels, not shown.

A handle feeding mechanism 26 is located on top of the machine 10 and includes a guide frame 27 to receive a quantity of strips of handles 19a therein in magazine fashion for rapid loading of the machine of such handles. For example, the handles 19a may be packaged in a container with a predetermined number of strips of handles in a stack and the entire stack of handles can be inserted into the guide frame 27 in a single maneuver. One such configuration can have 20 handles per strip and 25 strips of handles in each stack to allow

500 handles to be loaded into the guide frame of the magazine feeding mechanism 26 in a single simple operation.

A control panel 28 is mounted to one side of the handle-attaching machine 10 and contains the electrical circuitry necessary for operation of the machine. The control panel 28 while being shown in this particular location, can be located at any convenient place on the machine, preferably at a location to facilitate servicing of the machine without disrupting operation thereof, or at least with minimum interference with the transport of cartons therethrough. The control panel 28 may be located at the lower stand portion 12 and arranged to have the excess opening thereof at the back of the machine rather than facing forward so that repairs can be made quickly and easily.

Referring now to FIG. 2, the handle-attaching machine 10 is shown in perspective view looking at the machine from the input 16 and with the hood 13 thereof removed to show some of the interior mechanism of the machine. At the input 16 there is located the first sensing switch 29 which has a sensing arm to be actuated by the presence of a single carton 18 passing along the conveyor 20. A second sensing switch 30 is located rearwardly of the switch 29, that is in a direction opposite of the conveying direction. Upon actuation of the first switch 29, the machine will not be energized to initiate operation of the punching and handle-applying stations. However, upon accumulation of cartons on the conveyor 20 the second switch 30 is then actuated and after a predetermined time interval, actuation of these two switches, 29 and 30, will effect operation of energization of the machine. A drive motor will be energized and, according to this invention, a common cam shaft will rotate to operate the various stations of the machine. A timing wheel 31 is located at the sidewall of the machine and which has timing marks 32 thereon locatable in registry with timing wheel 31. The timing wheel 31 is connected to the end of the common cam shaft passing through the machine and when the timing marker thereon is in registry with the middle of the marks 32 the conveying path through the machine from inlet 16 to outlet 17 will be obstruction-free, i.e. stop mechanisms within the machine are ineffective, and milk cartons transported along the conveyor 20 will pass through the machine without apertures being formed in the upstanding ridge nor handles being applied thereto. The timing wheel 31 may be either directly connected to the cam shaft or indirectly as through a gear connection.

55 A plurality of horizontally disposed guide rollers 33 are located at the input 16 to receive and guide each carton 18 as it is transported to a first stop member 34 which defines a punching station within the machine 10. The stop member 34 may take the form of an arm, as seen in FIG. 4, which extends transversely of the conveying path to abut with the gable-top portion of the carton 18. When the carton is stopped the conveyor belt 20 may continue to move thereunder and only a slight frictional force will be exerted and thus no damage will occur to the carton. A movable frame support 36 carries the stop arm 34 and can be unlocked, by a pair of unlocking knobs 37 on each side of the machine, and pivoted away from the conveying path as shown by the arrow 38. The displaced position of the stop arm 34 is shown in broken line and indicated by reference numeral 34a. By so displacing the stop arm

34 from its operating position, cartons will pass through the machine without having handles attached thereto.

As best seen in FIGS. 1, 2 and 4 the movable frame support 36 has a pair of end support members 39 and 40 connected together by a rectangular bar 41 and a square bar 42. The square bar 42 may be displaced angularly with the corners extending up and down and to the side as best seen in FIG. 4. The longitudinal bars 41 and 42 provide sufficient rigidity of the movable frame support 36 so that the stop arm 34 will be held firmly at a fixed position to stop the carton precisely at the punching station location so that a punching mechanism will be accurately positioned over the gabled-top of the carton to punch an aperture therethrough precisely at a given location.

Referring now to FIG. 3, a somewhat diagrammatic top view of the machine 10 is shown with portions thereof broken away for clarity. A plurality of cartons 18 are transported into the machine and a first carton abuts with the stop bar 34 to be positioned at a punching station designated generally by reference numeral 43. The punching station 43 includes a hollow arm member 44 extending transversely of the machine and includes hole punching means 46 carried at the free end of the arm 44 and a pivot point 47 is located near the other end of the arm and spaced from a main cam shaft 48. The cam shaft 48 operates substantially all of the functions of the machine in synchronization with the various lobe positions on the cam. By utilizing a common cam shaft to synchronize the operation of the machine a minimum amount of compressed air is required to operate the machine and therefore is of substantial significance in dairy operation. While the carton 18 is at the punching station 43 a hole is formed in the upstanding ridge 18a of the carton by having the hollow arm member 44 pivot downwardly about the pivot point 47 to cause the punching mechanism 46 to embrace the ridge 18a. A second cam actuating means is manipulated by the cam shaft 18 and includes a push rod extending through the hollow arm 44 to cause actuation of the punching mechanism 46. After the hole is formed the cam shaft 48 will cause the hollow arm 44 to raise upwardly free from the upstanding edge 18a.

After the hollow arm 44 is raised a pusher bar 49 is actuated, this also being done by a cam follower means on the shaft 48, to cause the carton 18 to be shifted transversely of the conveying path. The pusher bar 49 is connected to a pair of guide rods 50 and 51 which reciprocate in guide blocks 52 and 53, respectively, under the control of the main cam shaft 48. The pusher bar 49 will shift the carton 18 transversely of the conveying path until the carton engages a plurality of stop rollers 54. Also during this transverse movement of the carton the carton is freed from the stop arm 34 and will continue to be conveyed under the influence of the conveyor 20. A plurality of angularly displaced guide rollers 56 will again direct the carton 18 back on the central portion of the conveyor 20 where the carton will pass between the guide rollers 57. The carton is once again in alignment on the conveyor and will engage a second stop arm 58.

When the carton stops at the second stop arm 58 it is in registry with a handle-applying station designated generally by reference numeral 59. The handle-applying station 59 includes a handle-applying mechanism 60 positioned over the conveying path. Carton raising means are then actuated by a cam-operated air

valve 25 (FIG. 1) which, in turn, controls an air cylinder to raise the carton into position so that the upstanding ridge 18a is positioned in registry with the handle-applying mechanism 60. The handle-applying mechanism 60 will then sever one of the handles 19 from the strip of handles 19a and apply the handle to the carton in a manner to be more fully described hereinbelow. When the handle is applied to the carton the carton is then lowered into the conveyor 20 and the push bar 49 again is actuated to shift the carton transversely of the conveying path whereupon the carton will engage the stop rollers 63. The carton is then conveyed along the conveyor and abuts against a plurality of angularly displaced guide rollers 64 which, in turn, direct the carton back into a central position on the conveyor and between a plurality of output guide rollers 66. The carton then passes from the handle-attaching machine 10 to the output opening 17 whereupon the carton is transported for packaging into crates or the like.

20 The handle-applying mechanism 60 is operated by a pair of push rods 61 and 62 which are connected to the main cam shaft 48 by suitable cam-follower means to operate in synchronism with other functions of the machine. As mentioned above FIG. 3 is somewhat diagrammatic and the push rods 61 and 62 may be positioned over one another rather than side by side.

It will be noted that as the first carton 18 passes from the first stop arm 34 to the second stop arm 58 a second carton is positioned against the first stop arm 34. 30 Therefore there will be two cartons stopped at the same time along the conveying path, one carton being positioned at the punching station 43 and the second carton being positioned at the handle applying station 59. By proper timing of the main cam shaft 48 a hole will be punched in a first carton 18 at the same time a handle is applied to a second carton 18. Therefore as the pusher bar 49 is manipulated transversely to the direction of travel of cartons passing through the machine, it will dislodge two cartons at a time from their respective work stations.

40 For a better understanding of the details of construction of portions of the handle-attaching machine 10 reference is now made to FIGS. 5 and 6 which show a portion of the main cam shaft 48. Here the end wall 67 represents the input side of the machine and the cam 48, in FIG. 5, is viewed from the rear of the machine. The cam shaft 48 includes a drive gear 68 fastened thereto and this gear is in engagement with the driving gear connected to suitable electric motor means, not shown. 45 A cam operated switch 69 is mounted to an arm 69a extending from the wall 67, and has a cam-follower or roller 70 engaging a cam lobe 71. Each revolution of the cam shaft will cause the switch 69 to be actuated to register a count in an accumulation counter within the control circuit of the machine.

50 For the punching station a pair of cams 72 and 73 are provided to operate the punch mechanism 46. For example the cam 72 will actuate a linearly movable arm (not seen) which, in turn, reciprocates the shaft within the hollow arm 44 to operate the punch mechanism 46. The cam 73 engages a cam-follower 74 connected to an arm 76 which, in turn, causes the hollow arm 44, FIG. 3, to be raised and lowered about the pivot 47, FIG. 3.

55 A roller and cam-follower 77 is arranged for movement along the longitudinal axis of the cam shaft 48 and is referred to as a longhorn roller. The longhorn roller 77 moves between cam guide surfaces 78 to pro-

vide reciprocating action of a handle advancing mechanism which is used to advance the lowermost strip of handles 19a one handle at a time so that a handle is at all times positioned in the handle-attaching mechanism. A second axially movable roller 79 is connected to an arm 90 by a stud or bolt 81. When the roller 79 engages the lobe 139 the arm 80 operates a handle pushoff device which ultimately severs the attached handle from the strip of handles and pushes the attached handle downwardly onto the top of the carton during the final stages of attachment.

Referring now to FIGS. 7, 8 and 9, the punching station 43 is shown in greater detail. FIG. 7 is viewed through the endwall 67 and shows a carton 18 in position at the punching station 43 with the punching mechanism 46 already lowered upon the upstanding ridge 18a just prior to forming the aperture there-through. The hollow arm 44 is pivoted at 46 of the arm 76 and moves therewith. Also a push rod member 82 is located within the hollow arm for reciprocal movement therein in response to the cam 72. At the end of the push rod 82 is located a punch 83 which is in alignment with a die 84, the punch 83 and the die 84 being located on opposite sides of the upstanding ridge 18a and form the punching mechanism 46. As the cams 72 and 73 rotate the cam follower 74 allows the arm 44 to be lowered while the second cam follower 85 engages the cam surface 72 to cause the punch 83 and die 84 to come together and form an aperture through the upstanding ridge 18a. The plug or struck-out material formed by the punch 83 is extracted through the die 84 by a vacuum extract line 89. The raising and lowering of the hollow arm 44 is accomplished by the rod 76 which is pivoted at 47 and has a roller 87 engaging the underside of the arm 44. Pivotal movement of the rod 76 about its shaft 86 will cause similar pivotal movement of the arm 44 about its pivot point 47. As the cam 73 continues to rotate the cam-follower 74 will cause the roller 87 to move upwardly and raise the hollow arm 44 to be free of the gable-topped carton so that the carton can be shifted transversely of the conveying path and around the stop 34 to continue its movement along the conveying path. The push rod 82 is spring-biased by a spring 88 to maintain the cam-follower 85 in firm contact with the cam 72. However, other suitable spring-biasing means may be incorporated as desired.

Also shown in FIG. 7 is the guide rod 51 passing through the guide blocks 53 located at the opposite end wall of the machine 10. The guide rod 51 has a depending arm 90 with a roller 91 attached to the lower end thereof. The roller 91 engages a corresponding cam surface, not seen, on the main cam shaft 48 and reciprocates the rod left to right, as is seen in FIG. 7, to move the pusher assembly 36 back and forth after each operation on the cartons in the respective work stations. The rod 51 may be suitably spring-biased by any means and a gear 92 is connected to a longitudinally extending shaft 93 which, in turn, is connected to the other guide rod 50 at the input side of the machine. The shaft 93 is then rotated back and forth in response to the gear racks 94 located at the end of the rod 51. This will maintain substantially linear movement of the entire pusher mechanism.

For a better understanding of the pusher mechanism 36 and its connection to the guide rods 50 and 51, reference is now made to the somewhat diagrammatic

showing of FIG. 10. Here only a fragmentary portion of the output wall 67a is shown while substantial portions of the rear wall 67 is shown with the rear of the machine broken away to illustrate a fragment of the main cam shaft 48. The view of FIG. 10 is taken from the output of the machine at the rear side thereof. Here it can be seen that a cam 96 has an inside cam track along which the cam-follower 91 rotates while the cam shaft 48 is rotated. This will cause reciprocal linear movement of the guide bars 50 and 51 via the gear and rack 92 and 94, respectively, and a corresponding gear end rack 97 and 98 at the other end of the shaft 93. A pair of depending bars 99 and 100 are firmly secured to the rods 50 and 51, respectively, and have the pusher 36 and the stop mechanisms 34 and 58 fastened to the lower end thereof. Therefore cartons which are located at the punching and handle-applying stations can be moved out of engagement with the respective stop means so that the cartons will continue their transport through the machine.

Referring now to FIGS. 11, 12 and 13, a handle-feeding mechanism is shown in perspective and fragmentary views with only the essential components shown, and is designated generally by reference numeral 100. The handle-feeding mechanism 100 advances a strip of handles 19a into the handle-attaching mechanism one handle increment at a time, whereupon the handle then being applied to a carton is severed from the strip. Here it is more clearly seen that the cam-follower 77 engages the cam surfaces 78 for back and forth movement as mentioned above with regard to FIG. 5. The cam-follower 77 is connected to one end of a pivotal arm 102 which has bent portions 103 and 104 extending outwardly from a central portion thereof. The central portion of the arm 102 is pivoted by a stud or bolt 106 which is secured to a support frame of the machine, of which only a fragmentary portion 107 is shown. As the cam-follower 77 is actuated from left to right by the main cam shaft 48 the arm will pivot about the stud 106.

A saddle 108 is located over the handle-applying station 59 and receives a strip of handles. The saddle 108 may be of any suitable configuration, but preferably has a flat top wall and angularly displaced side walls as shown in FIGS. 11 and 12. A feeder or handle advancing member 109 is positioned under the saddle 108 and has diametrically opposed side fingers 110 and 111 extending through apertures 112 and 113, respectively, of the saddle 108. Also, a pair of upstanding fingers 114 and 116 pass through an aperture 117 in the top wall of the saddle 108. The feeder 109 moves the strip of handles 19a one handle at a time into the handle-attaching mechanism. A connecting rod 118 is fastened to the bent end portion 104 of the pivotal arm 102 and to the feeder member 109 for back and forth movement thereof. It will be noted that the vertical extent of the slots 112 and 113 are substantially greater than the vertical extent of the fingers 110 and 111 passing there-through. This is to accommodate vertical movement of the fingers as well as forward and backward movement for advancing the strip of handles 19a. That is, the feeder member 109 is pushed forward along the arrowed line 119 to advance the handle to the handle-attaching position. Subsequent movement of the feeder member 109 is downward along the line 120 whereupon the upstanding fingers 114 and 115, together with the side fingers 110 and 111, disengage fully the strip

of handles 19a. Rearward motion of the feeder member 109 is then accomplished along the line 121, this motion being a retracting motion of an extent equal to the distance between handles of the strip of handles. The feeder member is then raised along the line 122 so that the fingers 114 and 116 together with the side fingers 110 and 111 again engage a handle of the strip of handles to advance the strip so that a subsequent handle is positioned in the handle-attaching mechanism.

To more fully understand how the motion indicated by lines 119-121 is accomplished, reference is now made to FIGS. 14 and 15 which show further cam surfaces and cam follower means to effect this motion. FIG. 15 shows a portion of the main cam shaft 48 as having a cam 123 with an inner cam surface to receive a cam-follower 124. The cam-follower 124 is connected to one end of a V-shaped member 126 which acts as a bell-crank about a fixed shaft 127. The other end of the bell-crank 126 is connected to an actuating arm 128 by means of a link 129. A fixed shaft 130 rotates about its longitudinal axis and has firmly secured thereto an arm 131 which receives the shaft 130 at substantially a central location thereof. During rotational movement of the shaft 130 the arm 131 will have the ends thereof move upwardly and downwardly so that a depending link 132 at the farthest end of the arm will raise and lower the shaft 118 to effect the motions as indicated by the lines 120 and 122 of FIG. 11. The other end of the arm 131 actuates a switch 133 by means of a depending actuator 134. The switch 133 is a counter switch and applies pulses to an accumulation counter within the control circuitry of the machine. Each time the strip of handles 19a is advanced and a handle removed, the counter switch 133 will register a count, and upon the accumulation of 20 counts, this being the number of handles in a given strip 19a, a new strip of handles is positioned on the saddle. This is done by solenoid means which are energized to lower a second strip of handles into position on the saddle 108.

Referring now to FIG. 14, a handle push-off bar 136 is located at the end of the rod 118 and is used ultimately to sever the last possible connection between the handle just attached to a carton and the associated strip of handles 19a. The push-off bar 136 is connected to a solid rod 137 which passes through the rod 118 and has one end connected to a fastening block 138. The fastening block 138 is connected to the actuating arm 80, and as mentioned above with regard to FIG. 5, is actuated forward and backward by an abruptly-shaped cam surface 139 formed on the cam shaft 48, and which engages the opposite side of cam-follower 78 to produce the necessary quick acting motion of the pusher 136.

Referring now to FIG. 16, an end view of the handle-attaching machine 10 is shown looking into the machine from the input 16 thereof. A carton 18 is shown raised into position at the handle-attaching station and the magazine 26 is shown located over the conveying path with only the end handle of the lowermost strip of the handles 19a being positioned over the carton 18. The magazine 26 is shown having a stack of handles indicated by reference numeral 140, this stack of handles comprising a plurality of strips of handles 19a. The stack 140 may include 25 or more strips of handles of 20 handles per strip so that 500 handles can be loaded into the magazine at a single loading. The strips of handles 19a are lowered onto the saddle 108 one strip at

a time in accordance with the operation of magnetic actuating device 141 and 142. The magnetic actuating devices are energized in response to the counting circuit which counts the number of handles passing over the saddle 108 and, upon the 720th count, the magnetic actuators 141 and 142 are energized to lower another strip onto the saddle. Each 20th count will produce the same operating effect of the magnetic actuators 141 and 142. Upon lowering of the stack 140 to a predetermined minimum limit, a sensing switch may be actuated to energize a warning mechanism, such as a lamp or buzzer, so that the operator of the machine can insert another load of handles in stack form. A first pair of diametrically opposed rake-like members 143 and 144 support the next strip of handles 19a to be lowered onto the saddle 108. A second pair of diametrically opposed rake-like members 146 and 147, are located above the rake-like members 143 and 144, and support the entire remaining stack 140 of strips of handles so that unnecessary pressure is not applied to the strip of handles to be lowered onto the saddle. This also insures that the strip of handles on the saddle is free of all other handles and can readily slide along the saddle as the feeder member 109 pushes the strip of handles during each actuation thereof.

For a better understanding of the handle-feeding magazine 26, reference is now made to FIGS. 17-22 which illustrate the front and the side views of the magazine, together with a series of operating views. Referring now particularly to FIGS. 17 and 18, the guide frame 27 for the stack 140 of strips of handles 19a is shown positioned immediately over the saddle 108 for dropping the strips of handles thereon one strip at a time. An opening 150 is formed in an end plate 151 and has a configuration conforming to the shape of the handles as they are fed to a pair of handle-attaching arms 152 and 153 of the handle-attaching mechanism 60. A sensing switch 156 is positioned at one end of the support frame 27 and senses that the stack of handles has a predetermined number of strips in the stack. As the stack of handles decreases to a predetermined level, the sensing switch 156 will energize a suitable alarm, it being either a light or buzzer, to indicate to an operator that additional handles are to be inserted into the mechanism.

The support frame 27 has vertical center end pieces 27a and 27b, each having slots or grooves extending upwardly from the saddle 108. The end handle of each strip is provided with a central tab 190, FIG. 32, which is inserted into the slots or grooves and acts as a guide means for the stack of handles.

The magnetic actuators 141 and 142 are connected to the respective rake-like gate members by pivotal arms 157 and 158 which are geared together at an arcuate segment having gear teeth 157a and 158a formed therein. The arm 157 is pivoted about a shaft 159 while the arm 158 is pivoted about a shaft 160. The gate members 146 and 147 are connected to the arms 157 and 158 via the depending arms 161 and 162, respectively. Similarly, the gates 143 and 144 have depending arms 163 and 164 respectively for moving the gates and allowing dropping of the lowermost strip of handles onto the saddle 108. The depending arms 161 and 162 are connected to boss portions 166 and 167 respectively which have arcuately fashioned elongated slots 168 and 169 formed therein. A pin connects the boss portion to the depending arm and provides a slight lost

motion connection therewith for proper operation of the handle dropping mechanism. To manually operate the gates 143, 144, 146, and 147 a pair of knobs 170 and 171 are provided, and allow the operator to sequentially pull the knobs outwardly one at a time to actuate the gates in proper sequence and drop a strip of handles onto the saddle.

Reference is now made to FIGS. 19-22 which show the sequence of operation of the gates 143, 144, 146 and 147. FIGS. 20, 21 and 22 are only enlarged fragmentary portions showing the gates 144 and 147 at one side of the mechanism. In FIG. 19 the stack of handles 140, inserted into the support frame 27, has only one strip of handles 19a shown in solid lines for clarity. The strip of handles 19a rests upon the upper gates 146 and 147, this also supporting the entire stack of handles. Energization of the magnetic actuator 141 will cause the upper gates 146 and 147 to pivot outwardly, and drop the entire stack of handles onto the lower gates 143 and 144. This is best seen in FIG. 20, which shows the gate 147 being moved away from a supporting position and dropping the stack of handles 140 onto the lower gate 144. The next sequence of operation includes moving the gates 146 and 147 back into engaging position with the stack of handles, this being engaged now with the strip of handles immediately above the lowermost strip of handles. Also at this time the arm and arcuate surface 149 and 149a, respectively, pivot about their axis and allow the lowermost strip of handles 19a to drop below the gates 143 and 144 onto the arcuate surface 149a, as best seen in FIGS. 21 and 22. Further arcuate movements of the surface 149a will cause the strip of handles 19a to drop onto the saddle 108 whereupon it is fed in incremental fashion to the handle attaching mechanism as described above. After dropping of the lowermost strip of handles, the arcuate surface 149a and the gate 144 move back into position for the next operation.

Referring now to FIGS. 23 and 24, the details of the handle-applying station 59 are here shown. The cam shaft 48 includes a pair of cam surfaces 170 and 171 which manipulate cam-followers 172 and 173 respectively to actuate the push rods 61 and 62 during the handle-applying operation. The cam-follower 172 is connected to the push rod 61 by a pivotal link 174 which is secured to and pivots about a shaft 176. Similarly, the cam-follower 173 is connected to the push rod 62 by a pivotal arm 177, also secured to and pivoting about the shaft 176. The push rods 61 and 62 manipulate the handle-attaching arms 152 and 153 respectively to apply a handle 19, shown engaged therewith to the milk carton 18, which is located in the raised position at the handle-applying station. The handle-applying arms 152 and 153 are connected together for synchronous operation by arcuate geared segments 178 and 179 which are pivoted above stationary support studs 180 and 181 respectively. The lower ends of the arms 152 and 153 grasp the handle 19 which is at the extreme end of the strip of handles 19a and squeeze the ends of the handle together, this movement being to the left as viewed on the drawing. This action will sever the handle from the strip of handles as best illustrated in FIG. 24, which shows the handle-applying arms 151 and 152 in their fully locked together position, with the handle 19 attached to the upstanding ridge 18a of the carton 18. When the handle-applying arms 152 and 153 are brought together as mentioned

above, the stem 185 of the handle 19 passes through the aperture 18b of the upstanding ridge 18a and through an aperture 186 formed in the other end portion of the handle. When the handle-applying arms are 5 fully brought together, hammer or piston means to be described will flatten the stem 185 to cause cold flow of the material thereof, to form the flattened head 187. This will insure permanent attachment of the handle to the milk carton. No heat or other external means is used to cause the riveting action and only cold flow of the material will take place. After the handle 19 is attached to the carton 18, the handle-applying arms 152 and 153 are retracted from their closed position, and the pusher mechanism 36 will shift the carton 18 transversely of the main conveying path so that it will clear the stop 58. The carton will then continue to be conveyed to the output 17 of the machine 10.

FIGS. 25-28 illustrate in greater detail the handle attaching mechanism and the hammer means for deforming the stem of the handle to cold flow the material thereof. FIG. 25 shows the detaching arms 152, 153 in their open position, in readiness to receive a handle, not here shown, and their associated arcuate gear segments 178 and 179 respectively. Actuation of the push-rod 61 will actuate the gear segment 178 and it will pivot about its shaft 197. This will cause the associated gear segment 179 to pivot about its shaft 198 and the detaching arms 152 and 153 will arcuately move along their associated slots 195 and 196, respectively, which receive roller means 195a and 196a therein. These slots and rollers will guide the detaching arms 152 and 153 through an arcuate and somewhat displaced track or path so that a handle 19 can be peeled off the end position of the strip of handles and the ends thereof brought together so that the stem 185 is threaded through the aperture within the carton and through the aperture 186 in the other end of the handle.

FIG. 26 shows a handle in the fastened position, this 40 being illustrated in broken lines, with the hammer means 191 of the detaching arm 152 in a position to deform the stem of the handle. As best seen in FIG. 28, the hammer means includes a movable rod 192 which has a reduced diameter end portion 192a thereof extending in a direction opposite of the stem of the handle 19 and is spring biased by a spring 193. The rod 192 is urged into engagement with the stem by a hammer 194 which is controlled by the push rod 62, and the timing sequence of the detaching arms 152 and 153 45 and the hammer means 191 is controlled by the displacement of the cam lobes 170 and 171 of FIG. 24. This will urge the stems 192 against a back-up block 195 to cause deformation of the material forming the stem, i.e., cold flow of the material. The hammer 194 can be adjusted by a threaded nut 194a to determine 50 the amount of deformation for proper gripping of the stem. FIGS. 25-28, therefore, illustrate the greater part of the details of the handle attaching mechanism, and it will be understood that variations of the specific embodiment shown therein can be made without departing 55 from the spirit of this invention.

FIG. 29 clearly illustrates the gable-top carton 18 with the upstanding ridge 18a having an aperture formed therein. FIG. 30 shows the handle 19 secured to the upstanding ridge 18a with the deformed portion 187 shown, this being a cold flow rivet formation as 60 mentioned above.

FIGS. 31 and 32 illustrate a novel means of packaging a plurality of strips of handles in a stack to accommodate quick loading of the magazine feed mechanism of this invention. The stack of handles 140 is packaged in a container 300 with the stack in an upside down position. An upstanding stem 301 extends through the space between handles substantially centrally of the strips of handles. The upstanding stem 301 will facilitate removing the entire stack of handles from the carton in a single maneuver and thereby increase the efficiency of loading such handles into the machine. The operator merely grasps the upstanding stem 301 and removes the entire stack 140 of handles. The handles are then turned over as shown in FIG. 32, and the end tabs 190 are aligned with the upstanding guides of the support frame 27 and proper alignment is thereby achieved. The entire stack of handles is inserted into the support frame and the upstanding stem 301 (now inverted) as shown in FIG. 32, is readily removed. The upstanding stem 301 has a T-bar top 302 which engages several of the centrally located handles to provide means for removal of the stack from the container 300. However, other means may be provided to facilitate removing the entire stack of handles from the carton.

Referring now to FIGS. 33, 33A and 33B, there is seen an electrical circuit diagram of the control panel 28 for controlling the sequence of operation of the handle-applying machine 10. FIG. 33 illustrates the sequence in which FIGS. 33A and 33B are to be viewed next to one another. The schematic diagram illustrated herein also illustrates a wiring harness which has wiring leads connected to the corresponding switches and components within the schematic diagram. Therefore like reference numerals of components connected to the wiring harness are those components which are illustrated in the schematic diagram. The control circuit is arranged for connection to a three-line 220 volt source over a cable 200 which has a three contact control switch 201 having an independent contact connected in series with each of the lines. A plurality of fuses 202 are connected in series with each line for protection of the various components. A drive motor 203 is energized in response to closure of a plurality of contacts 204 connected in series with the power-applying lines. The drive motor 203 will have an output gear engageable with the gear 68 of the cam shaft 48, as shown in FIG. 5. A power supply transformer 206 may have a variable tapped primary winding 206a and a first variable tap output winding 206b and a second variable tap output winding 206c. The winding 206b may provide either 115 volts or 230 volts, as desired, for operating relays or the like. On the other hand, the secondary winding 206c provide a relatively low voltage, in the order of between 20 and 32 volts or so and this voltage is rectified by a bridge rectifier circuit 207 to provide a DC voltage of approximately 24 volts over a pair of lines 208 and 209. The main power switch 210 is connected in the low voltage line and this switch will energize a relay 204a which controls actuation of the contacts 204 for the motor 203. The relay 204a is energized through a relay contact 211 and a switch contact 212 or by either one of parallel lines having switches 213 and 214 therein. A time relay switch 216 is connected in series with the switch 213 and is paralleled by a relay contact 217. A second relay 218 is energized in response to closure of a series connected switch 219

and a third relay 220 is energized in response to the closure switch 221.

- An impulse counter 224 has one input thereof connected to a switch 226 and another input thereof connected to a switch 227. An indicating lamp 228 is energized in response to closure of a switch 229. The indicating lamp 228 may be the warning light for the handle-receiving magazine and the switch 229 is the handle-sensing switch 156, of FIG. 17.
- 10 The counter 224 energizes the switch 230 which in turn controls energization of a relay 231. Relay 231 closes its associated normally open counter 232 and opens its normally closed contact 233 to energize a second relay 234, to control energization of an electromagnetic actuator 236 while the relay 231 controls energization of an electromagnetic actuator 237. The electromagnetic actuators 236 and 237 here correspond to the magnetic actuators 141 and 142 of the handle-receiving magazine as shown in FIGS. 17 and 20 18. A plurality of ganged-together switches 240, 241 and 242 will be operated by the relay 234, this being done in a sequential manner to lower the stack of handles one strip at a time onto the saddle, as mentioned hereinabove. A pair of relay contacts 243 and 244, normally open and normally closed, respectively, are actuated by the relay coil 231.

The circuit operation is as follows. With no cartons in the machine, when the main switch 210 is closed, the indicating light 214 is energized. This indicates that everything is ready for applying handles and that cartons may be conveyed into the machine 10. The magnetic actuators 236 and 237 are energized to lock the magazine closed. A first carton delivered into the machine will initially actuate the momentary switches 213 and 219 to a closed condition. These switches correspond to switches 30 and 29, respectively at the input of the machine as shown in FIG. 2. The quick action of switch 213 will not allow the relay 218 to become energized. However, when a build-up of cartons occurs at the input of the machine 10 the switch 219 will remain closed for a longer period of time sufficient to energize the relay 218 and close contact 216. This will cause the relay 204a to become energized and apply operating power to the motor 203 and the handle-attaching machine will be set into operation as cartons 18 continue to be conveyed into the machine. During operation the momentary switch 221 is actuated to energize the relay 220 and produce a pulse at the input of the counter 224 by closure of the contact 226. After 20 counts by the switch 226, the counter 224 automatically goes back to zero and the contacts 230 are closed for a short period of time, this being in the order of 250 milliseconds or so, to energize the relay 231. This will cause closure of the contacts 243 which, in turn, will energize the relay 234 and start operation of the magnetic actuating devices 236 and 237 so that a new strip of handles can be positioned from the stack onto the saddle 108 thereunder.

60 When switch 213 opens, as a result of no more cartons being accumulated at the input of the machine, the motor 203 will be deenergized and the machine will stop running. However, there will remain, in the embodiment disclosed herein, two cartons in the machine and these cartons can be fed through the machine by handle manipulation of the wheel 31.

65 What has been described is an efficient and easily maintained handle-attaching machine for applying piv-

otal handles to the top of cartons such as milk cartons or the like. While only a single embodiment of the total machine is disclosed herein, it will be understood that variations and modifications may be effected without departing from the spirit and scope of the novel concepts disclosed and claimed herein.

The invention is claimed as follows:

1. A machine for applying handles to cartons comprising, conveying path means through the machine along which a plurality of cartons are to be transported, a punching station having punch means thereat and extending toward said conveying path means for forming an aperture in a handle-receiving portion of each carton as it passes said punching station, a handle-stacking station having support and guide means for holding a plurality of similarly oriented strips of handles, handle-feeding means to advance a strip of handles one handle at a time, and a handle-applying station having handle-holding and applying arms to receive a single handle from said handle-stacking station automatically to sever said handle from its associated strip and applying said handle to the carton.

2. The machine of claim 1 further including stop means at said punching station temporarily to stop transport of the cartons passing therethrough, said punch means including a hollow support arm pivotal near one end thereof remote from said conveying path means and a punch mechanism at the free end of said arm and located over said conveying path means, a linearly movable rod passing through said hollow arm to actuate said punch mechanism, a rotatable cam shaft, first and second cam follower means associated with said cam shaft, said first cam follower means arranged to move said hollow arm downwardly over the carton when stopped by said stop means, and said second cam

follower means arranged to move said rod within said arm to actuate said punch mechanism, said first cam follower means being arranged for subsequently raising said arm to remove said punch mechanism from the carton.

3. The machine of claim 2 further including third cam follower means associated with said cam shaft, a link extending from said third cam follower means and connected to said handle-holding and applying arms to operate the same in timed relation with respect to said punch mechanism.

4. The machine of claim 3 which further includes means for operating said punch mechanism and said handle-holding and applying means simultaneously.

5. The machine of claim 3 further including a fourth cam follower means, a pusher linearly movable in the direction of said conveying path means to push said handle to a folded position after it is applied to the carton, and a second link connecting said fourth cam follower means and said pusher.

6. The machine of claim 1 further including sensing switches to sense the presence of cartons in the machine automatically to initiate operation of the machine and automatically to terminate operation of the machine when the cartons have decreased to a predetermined number.

7. The machine of claim 6 wherein said predetermined number of cartons is two.

8. The machine of claim 1 wherein said punch means is arranged to form apertures through the upwardly extending ridge portions of a gabled-top cartons.

9. The machine of claim 8 wherein said gabled-top carton is a milk carton.
